MAGNETICALLY CONTROLLED TOY VEHICLE
Vladimir Nyc, 3125 U St., Sacramento 17, Calif.
Filed Aug. 18, 1961, Ser. No. 132,444
6 Claims. (Cl. 46—236)

This invention relates to toy vehicles and more particularly to a means of maneuvering them.

It is an object of the present invention to provide a device for maneuvering of toy vehicles in a simple and efficient manner so that a person of any age may enjoy it.

Another object of the present invention is to provide the toy vehicle with a device to maneuver itself without outside help in such a manner so that the spectators will be amazed and puzzled at its antics.

Still a further object of the present invention is to provide a magnetically maneuvered toy vehicle that can be produced, packaged and sold in large quantities at a comparatively low cost.

Still additional objects, benefits, and advantages of this invention will become evident from a study of the following detailed description taken in conjunction with the accompanying drawing, in which:

FIGURE 1 is a side view of the present invention for a magnetically controlled toy vehicle shown in elevation and partly broken away;

FIGURE 2 is a top plan view of the invention shown in FIG. 1;

FIGURE 3 is a side view of the terminal and contact rods showing from 13—15 how the vehicle enters from forward drive to reverse after the left contact rod (L) strikes object;

FIGURE 4 is a side view of the terminal rod and contact rods showing from 16—18 how the vehicle enters from reverse into forward after the right contact rod (R) strikes an object;

FIGURE 5 is a plan of a portion of the cardboard sheet showing the wire track concealed within the cardboard sheet and specially placed objects which the contact rod strikes.

Referring now specifically to the drawing, a magnetically controlled toy vehicle made in accordance with the present invention is shown to include a toy vehicle operated by a battery driven electric motor 1 with its steering controlled by magnets. A front magnet 2 is connected under the front axle 3 that has a vertical axis 4 extending from the center of it to the body of the vehicle. This vertical axis 4 makes it possible for the front axle 3 to rotate around it, allowing the vehicle to be steered. Under the rear end of the toy vehicle is a stabilizer magnet 5 to prevent the rear end from swaying from side to side and to make better turns. When the vehicle is in motion these magnets glide over a wire made of magnetically attracted metal that is concealed within a sheet of cardboard. The magnets under the vehicle keep it on course and control the steering. Another method of steering the toy vehicle with magnets is to use round magnets for wheels. This method could require two tracks within the sheet of cardboard unless only one magnet wheel is used on a vehicle, as for example a motorbike.

A terminal rod 6 is connected to a connecting rod 7 that has a contact rod 8 on each side of it. They are left contact rod (L) and right contact rod (R) and both point in opposite directions. The terminal rod 6 has two wires leading to it from the motor to form two contacts 10 on it. On each side of the terminal rod 6 there are two terminals 11 and 12 from the battery connected cross-wise to each other so that the terminals on one side are first plus and then minus and on the other side are minus then plus. When the terminal rod 6 is not in contact with

2

the terminals on either side it is in neutral 14 but when the terminal rod 6 is moved forward so that the terminal rod contacts meet the forward battery terminals, the vehicle is put in reverse 15 and when it is moved back to 5 the other two terminals it puts the vehicle in forward motion 18. The terminal rod 6 is made to move when one of two contact rods 8 strikes a specially placed object, possibly in the form of a pebble. When the vehicle is going forward the left contact rod (L) strikes a small object 21 which brings the terminal rod into neutral position 14. When the same left contact rod (L) strikes a slightly larger object 22 it forces the terminal rod to move forward 15 and comes in contact with the forward battery terminals, putting the vehicle in reverse. As the 10 vehicle is traveling in reverse the right contact rod (R) strikes a small object 24 that places the terminal rod into neutral position 17, and then into forward position 18 after the striking of another object 25 that moves the terminal rod in the other direction. Although the motor 15 does not work while the vehicle is in neutral position the momentum carries the vehicle far enough for one of the contact rods 8 to strike a larger object putting the vehicle either in reverse or forward. When there are a 20 number of wires joining as in FIGURE 5 there is the 25 possibility that when the vehicle returns backward along wire 23 after being set in reverse by object 22 that it would return to its starting position on wire 20. To prevent this from occurring wire 20 is terminated a short distance in front of wire 23 just far enough so that the magnets 30 under the vehicle do not engage with wire 20 upon returning.

The operation of this device will now be readily understood. When the vehicle starts off at the track 20 the magnets are attracted by the wire within the cardboard, 35 thus the vehicle shall follow the wire although it is not visible to the spectators. When the wire curves as wire 20 in FIGURE 5 the front magnet 2 turns the front axle 3 accordingly making a correct turn. An object 21 placed on the left of the vehicle's route is struck by the left contact rod (L) FIGURE 3, 13 moving the terminal rod 6 into neutral position 14. Further up, 14, another object 22 on the same side but slightly larger puts the vehicle in reverse 15 via left contact rod (L). As the vehicle is traveling backwards a gap between wire 20 and 23 assures 40 that the vehicle will not return back along wire 20 but 45 that the vehicle will continue on wire 23 where object 24 puts the vehicle in neutral 16 via right contact rod (R). The object 25 is struck by right contact rod (R) 17 placing the vehicle in forward 18.

50 While this invention has been described with particular reference to the construction shown in the drawing and while various changes may be made in the detail construction, it shall be understood that such changes shall be within the spirit and scope of the present invention 55 as defined by the appended claims.

Having thus completely and fully described the invention, what is now claimed as new and desired to be protected by Letters Patent of the United States is:

- 60 1. A magnetically controlled toy vehicle comprising:
  - (a) an elongated toy vehicle frame supported on ground engaging wheels;
  - (b) a battery powered electric motor mounted on said frame adapted to drive said wheels;
  - (c) reversible switch means interposed between said battery and said motor for reversing the direction of rotation of said motor;
  - (d) a track of magnetically attracted material beneath said vehicle frame;
  - (e) magnetic means on said frame attractable to said track for guiding said frame along the path of said track;
  - (f) a pair of rockable contact rods depending from

said frame on opposite sides of said track, means connecting said contact rods to said switch means to reverse said switch means in dependence upon the degree of angularity of said contact rods; and (g) a plurality of objects disposed in predetermined locations on opposite sides of said track in interfering relation with said contact rods, each of said objects being capable of angularly rocking the interfering one of said rods.

2. The device of claim 1 further characterized by an additional track of magnetically attracted material located beneath said vehicle frame, said additional track being arcuate and terminating adjacent one end in substantially tangential relation with respect to said first track.

3. The device of claim 2 wherein said one end of said additional track is spaced from said first track a predetermined distance.

4. A magnetically controlled toy vehicle comprising, in combination:

- (a) a battery driven electric motor;
- (b) a terminal rod;
- (c) two contacts on said terminal rod electrically connected to said motor;
- (d) a connecting rod;
- (e) a front axle pivotal about a vertical axis;
- (f) a wire track made of magnetically attracted material;
- (g) a pair of magnets, one of said magnets being a front magnet and affixed to said front axle in such a

5

15

20

25

manner as to follow said wire track and steer said front axle accordingly, the other of said magnets being a stabilizer magnet and connected under the rear end of the vehicle and also following said track;

(h) a pair of contact rods joined together by the said connecting rod to which also is joined the said terminal rod such that when either of the said contact rods strikes an object the said terminal rod will tilt in the opposite direction; and,

(i) a set of two battery terminals located on opposite sides of the said terminal rod, both sets being connected cross-wise to each other so that the said contacts on said terminal rod connected to said motor may meet either set of said battery terminals to reverse the current in said motor.

5. The toy vehicle of claim 4, said pair of contact rods consisting of two low lying oblique rods both pointing in opposite directions.

6. The toy vehicle of claim 4, said wire track being concealed within a sheet of cardboard.
